(57) **CLAIM**

The ornamental design for an audio device with display, as shown and described.

DESCRIPTION

FIG. 1 is a top front perspective view of an audio device with display showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof;

FIG. 7 is a bottom view thereof; and,

FIG. 8 is a top rear perspective view thereof.

The broken lines in the drawing figures depict portions of the audio device with display which form no part of the claimed design.

1 Claim, 7 Drawing Sheets
